Patented June 22, 1920.

INVENTOR

John H. Flynn Jr.

UNITED STATES PATENT OFFICE.

JOHN H. FLYNN, JR., OF CINCINNATI, OHIO.

DESIGN FOR A PULLEY-BLOCK.

55,508.

Specification for Design. Patented June 22, 1920.

Application filed March 20, 1920. Serial No. 367,490. Term of patent 14 years.

To all whom it may concern:

Be it known that I, JOHN H. FLYNN, Jr., a citizen of the United States, residing at Cincinnati, in the county of Hamilton and State of Ohio, have invented a new, original, and ornamental Design for a Pulley-Block, of which the following is a specification, reference being had to the accompanying drawing, forming part thereof.

The figures are perspective views of re-

verse sides of a pulley block showing the exterior appearance of my new design.

I claim:

The ornamental design for a pulley block as shown.

JOHN H. FLYNN, JR.
